(71) Applicant: **Graco Minnesota Inc.**, Minneapolis,
MN (US)

See application file for complete search history.

(72) Inventors: **Daniel P. Ross**, Vadnais Heights, MN
(US); **Samuel R. Stewart**, Minneapolis,
MN (US); **Jacob R. Whiteoak**, Blaine,
MN (US); **Jack A. Bosak**, Coon
Rapids, MN (US)

(73) Assignee: **Graco Minnesota Inc.**, Minneapolis,
MN (US)

(**) Term: **15 Years**

(21) Appl. No.: **29/934,233**

(22) Filed: **Mar. 25, 2024**

Related U.S. Application Data

(60) Continuation of application No. 17/886,667, filed on
Aug. 12, 2022, now Pat. No. 11,896,992, which is a
division of application No. 16/664,073, filed on Oct.
25, 2019, now Pat. No. 11,413,635.

CLAIM

The ornamental design for a component mixing chamber as shown and described.

DESCRIPTION

FIG. 1 is an isometric view of a component mixing chamber; FIG. 2 is a top plan view of the component mixing chamber;

FIG. 3 is a left side elevational view of the component mixing chamber;

FIG. 4 is a right side elevational view of the component mixing chamber;

FIG. 5 is a bottom plan view of the component mixing chamber;

FIG. 6 is a front elevational view of the component mixing chamber; and,

FIG. 7 is a rear elevational view of the component mixing chamber.

The broken lines in the figures show portions of a component mixing chamber and form no part of the claimed design.
